WATER HEATING APPARATUS

Filed April 24, 1944

FIG. 2 THOMAS A. BUCKLES
INVENTOR.

BY
James D. Givens,
ATTORNEY.

UNITED STATES PATENT OFFICE

2,423,578

WATER-HEATING APPARATUS

Thomas A. Buckles, Portland, Oreg.

Application April 24, 1944, Serial No. 532,537

1 Claim. (Cl. 219—39)

This invention relates to improvements in water heaters and has for its principal object the provision of means for controlling the circulation of the water through the heating element and also valve means for controlling the cold water supply to the interior of the tank through the bottom end thereof, said valve means also preventing circulation or mixing of the cold water with the heated water at all times.

The foregoing and other objects will appear as my invention is more fully hereinafter described in the following specification illustrated in the accompanying drawing, and finally pointed out in the appended claim.

In the drawing:

Figure 1 is a sectional side elevation of a water heater made in accordance with my invention.

Figure 2 is a sectional plan view taken on the line 2—2 of Figure 1.

Referring now more particularly to the drawing:

Reference numeral 1 indicates a water boiler of more or less conventional design surrounded by a jacket of insulating material 2 and encased by an outer cylindrical casing 3. The lowermost end of the casing is turned inwardly as at 4 to support itself, the insulating material and the tank 1 upon any approved form of base, generally indicated at 5. The upper end of the outer casing 3 is provided with a removable lid portion 6. Secured to and extending through the bottom wall 7 of the boiler 1 is a heating unit generally indicated at 8, within which is enclosed an electrical heating element 9 supplied with electrical energy from any convenient source of supply by means of cables 10. The housing of the heating unit is of greater diameter than the heating element 9 to provide a space to receive a supply of water coming from a pipe 11 connected through a valve control means, generally indicated at 12, with a water supply pipe 12A. The uppermost end of the heating unit 8 is slotted as at 13 to allow the heated water coming up through the element 8 to be delivered to the interior of the boiler 1. This end of the heating unit is embraced by and disposed within a fitting 14 formed on the top wall 15 of the boiler and into this fitting is attached an elbow 16 connecting with a pipe 17 which through an elbow 18 connects with an outlet pipe 19 which extends downwardly alongside the tank and terminates within or below the base thereof and connects with a pipe connection to a hot-water outlet fixture (not shown).

A thermostat 20 extends through or into contact with the boiler to partake of the tempera-

ture thereof and is electrically connected in the supply circuit 10 in the conventional manner and is set to open and close the electrical circuit to the heating element at predetermined high and low temperatures, respectively, of the water in the boiler.

The valve control means 12, previously referred to, consists of a housing 21 whose upper end is closed as at 22 and formed with relatively large apertures 23. The interior of the housing is in open communication with the water supply pipe 12A, as at 24. The lowermost end of the housing terminates in a valve seat 25 to seat a fixed valve 26 formed integral with a hollow tubular stem or 15 vertical extension 27 closed at its upper end and formed with relatively small openings 28 in its wall. The stem is open through the valve 26 and in open communication with the pipe 11 connecting with the interior of the heating unit 8. 20 From the foregoing it will be apparent that water from the supply pipe 12A may flow through the valve housing, through the apertures 23 therein into the boiler and through the smaller openings 28 in the valve stem 27 into the interior of the 25 heating unit 8.

The operation of the invention is as follows: Assuming that the boiler has just been installed and filled with cold water which comes up through the intake 12A through the valve housing 21, 30 apertures 23 therein and into the boiler to fill the same. Water also passes through the apertures 28 in the upper end of the valve stem thence through the pipe 11 and into the heating unit 8 which houses the heating element 9. 35 When this is accomplished, the thermostat 20 closes the circuit 10 to the heating element 9 and the same heats the water within the heating unit 8. This heated water of course rises to the top of the heating unit and enters the boiler through 40 the slots 13 in the upper end of the heating unit. Eventually of course the entire contents of the boiler become heated and with all outlets closed the hot water circulates upwardly and the cold water downwardly through the valve 12 and into 45 the heating unit. When the outlet fixture (not shown) is open and the hot water is being drawn off, the circulation stops and as the hot water is drawn out through the slots 13 in the heating unit 8 at its upper end and through the outlet 50 pipe 17, cold water enters the bottom of the boiler through the valve housing 21, through the apertures 28 in the upper end of the hollow valve stem 20 then through the pipe 11 to the interior of the heating unit. The water being heated by the 55 unit travels upwardly therein and of course draws

the cold water from the bottom of the boiler through the apertures 23 into the hollow valve stem and into the bottom of the heating unit. Thus the water in the boiler circulates through the valve into the heating element and out of the top thereof into the upper end of the boiler.

Assuming now, that the boiler is filled with hot water and through the medium of the thermostat the heating element is off and hot water is being drawn from the top of the boiler, then the cold water entering the bottom of the boiler, through the large openings 23 of the valve housing, is prevented from backing down through the hollow stem 27 and into the heating unit since in the absence of heat therein there is no upward pull or upward movement of the water in the heating unit, thus the system is now rendered non-circulating. Conversely when the heating element is heating circulation is created by the water passing upwardly therethrough and consequently drawing cold water from the supply pipe 12A through the hollow stem 27, pipe 11 and into the heating element. Briefly stated it may be said that when the heat is on circulation is created; when the heat is off the system is non-circulating.

While I have shown a particular form of embodiment of my invention, I am aware that many minor changes therein will readily suggest themselves to others skilled in the art without departing from the spirit and scope of the invention.

Having thus described my invention, what I claim as new and desire to protect by Letters Patent is:

A water heater comprising a boiler closed at both of its ends, a heating unit extending through both ends of the boiler and in open communication near its upper end with the interior of the

5
10
15

boiler, an outlet pipe in communication with the uppermost end of the heating unit and extending downwardly and outwardly into communication with an outlet fixture, a cold water supply pipe in communication with the interior of the boiler at the lowermost end of the heating unit through a valve means extending through the bottom wall of the boiler into communication with the interior thereof, said valve means consisting of a vertically disposed hollow body member in communication through apertures at its upper end with the interior of the boiler and in communication near its lower end with a cold water supply pipe, a fixed hollow valve stem disposed within the valve housing and terminating at its lowermost end in a hollow valve fixedly seated in the bottom of the valve housing and in communication with a pipe for directing cold water to the interior of said heating unit, whereby upward movement of the heated water within the heating unit draws cold water from the cold water supply pipe through said hollow valve stem and into the heating unit.
